(57) **CLAIM**

The ornamental design for a jewelry making accessories set as shown and described.

DESCRIPTION

FIG. 1 is perspective view of a jewelry making accessories set showing my new design;

FIG. 2 is a perspective view of a first component of the jewelry making accessories set, shown separately for ease of illustration;

FIG. 3 is another perspective view thereof;

FIG. 4 is a front elevational view thereof;

FIG. 5 is a rear elevational view thereof;

FIG. 6 is a left side elevational view thereof;

FIG. 7 is a right side elevational view thereof;

FIG. 8 is a top plan view thereof;

FIG. 9 is a bottom plan view thereof;

FIG. 10 is a perspective view of a second component of the jewelry making accessories set, shown separately for ease of illustration;

FIG. 11 is another perspective view thereof;

FIG. 12 is a front elevational view thereof;

FIG. 13 is a rear elevational view thereof;

FIG. 14 is a left side elevational view thereof;

FIG. 15 is a right side elevational view thereof;

FIG. 16 is a top plan view thereof;

FIG. 17 is a bottom plan view thereof;

FIG. 18 is an enlarged view of portion 18 shown in FIG. 10;

FIG. 19 is an enlarged view of portion 19 shown in FIG. 11;

FIG. 20 is an enlarged view of portion 20 shown in FIG. 12;

FIG. 21 is an enlarged view of portion 21 shown in FIG. 13;

FIG. 22 is an enlarged view of portion 22 shown in FIG. 14;

FIG. 23 is an enlarged view of portion 23 shown in FIG. 15;

(Continued)

FIG. 24 is a perspective view of a third component of the jewelry making accessories set, shown separately for ease of illustration;
 FIG. 25 is another perspective view thereof;
 FIG. 26 is a front elevational view thereof;
 FIG. 27 is a rear elevational view thereof;
 FIG. 28 is a left side elevational view thereof;
 FIG. 29 is a right side elevational view thereof;
 FIG. 30 is a top plan view thereof;
 FIG. 31 is a bottom plan view thereof;
 FIG. 32 is an enlarged view of portion 32 shown in FIG. 24;
 FIG. 33 is an enlarged view of portion 33 shown in FIG. 25;
 FIG. 34 is an enlarged view of portion 34 shown in FIG. 26;
 FIG. 35 is an enlarged view of portion 35 shown in FIG. 27;
 FIG. 36 is an enlarged view of portion 36 shown in FIG. 28;
 FIG. 37 is an enlarged view of portion 37 shown in FIG. 29;
 FIG. 38 is a perspective view of a fourth component of the jewelry making accessories set, shown separately for ease of illustration;
 FIG. 39 is another perspective view thereof;
 FIG. 40 is a front elevational view thereof;
 FIG. 41 is a rear elevational view thereof;
 FIG. 42 is a left side elevational view thereof;
 FIG. 43 is a right side elevational view thereof;
 FIG. 44 is a top plan view thereof;
 FIG. 45 is a bottom plan view thereof;
 FIG. 46 is an enlarged view of portion 46 shown in FIG. 38;
 FIG. 47 is an enlarged view of portion 47 shown in FIG. 42; and,
 FIG. 48 is an enlarged view of portion 48 shown in FIG. 45. The dash-dash broken lines in the drawings depict portions of the jewelry making accessories set that form no part of the claimed design. The dot-dash broken lines represent boundaries of the enlarged portions and form no part of the claimed design.
